UNITED STATES PATENT OFFICE.

HUGO WERNER, OF NEW YORK, N. Y., ASSIGNOR TO ROBERT BEATTIE & SONS, OF SAME PLACE.

DESIGN FOR CARPET.

SPECIFICATION forming part of Design No. 24,048, dated February 19, 1895.

Application filed January 25, 1895. Serial No. 536,275. Term of patent 3½ years.

To all whom it may concern:

Be it known that I, HUGO WERNER, a citizen of the United States, residing at New York city, in the county and State of New York, 5 have invented and produced a new and original Design for Carpets, of which the following is a specification, reference being had to the accompanying drawing, forming a part thereof, in which is represented a face view of the

10 carpet in which the new design is embodied.

The invention relates to a design to be worked into or upon surfaces such as carpets or similar fabrics, and it consists in the novel configuration of the figures therein as shown 15 and claimed.

The design consists of a body A and a border B.

The body A is decorated with a series of connected leaf scrolls, all the members of the 20 scrolls being made up of leaf figures distinct in themselves, and appearing one to overlap the other, the main stem of the main scroll having a petal formation from which the bunchings of leaves appear to emanate, and

the main scroll figure just described terminates in a floral effect. The side scroll figures, or those which connect with the main scroll figure, have all the characteristics of the main scroll figure; and the series of connected scrolls are so closely coiled or connected as to cover to a maximum degree the ground upon which they are produced.

The border B is decorated in substantially the same manner as the body, and is separated from the body by a dado of connected 30 trefoil figures.

I claim—

1. In a design for a carpet the body A, substantially as shown.
2. In a design for a carpet the border B, 40 substantially as shown.
3. The design for carpets, consisting of the body A and the border B, substantially as shown.

HUGO WERNER.
